(57) **CLAIM**

The ornamental design for a housing, as shown and described.

DESCRIPTION

FIG. 1 is a perspective view of our new ornamental design for a housing;

FIG. 2 is a top plan view thereof;

FIG. 3 is a bottom plan view thereof;

FIG. 4 is a right side elevational view thereof, the left side being a mirror image thereof; and,

FIG. 5 is a front side elevational view thereof, the back side being a mirror image thereof.

The phantom lines illustrating power cords connected to the housing in FIG. 1 are environmental and form no part of the claimed design.
